ELECTRICAL WEFT DETECTOR FOR LOOMS

Application filed December 2, 1929. Serial No. 410,901.

This invention relates to improvements in weft detectors for looms and more particularly to an improved electrical detector which may be used in connection with a metallic or 5 current conducting support for the weft bobbin or cop.

Certain forms of shuttles are provided with metallic spindles which support a hollow shuttle fitted over it and held thereto frictionally. It is an important object of my present invention to provide positively and negatively charged yarn contacting elements which upon occurrence of substantial exhaustion of weft may have electric contact 15 with the spindle to close a circuit external to the shuttle and effective to produce a change in the operation of the loom.

In the type of shuttle referred to it is common to employ paper tubes on which the 20 weft is wound, and it is a further object of my present invention to perforate such a tube at a plurality of points to cooperate with groups of plungers or needles, the perforations to be uncovered at weft exhaustion to 25 permit the needles to pass therethrough and have direct contact with the metallic spindle.

It is common experience that a shuttle will rebound slightly so that it is not always possible to forecast its exact location at the time 30 the detector cooperates with it, and it is a further object of my invention to arrange the perforations in such a way that one or another of the contacting plungers or needles will always be in position to pass through a 35 perforation irrespective of the location of the shuttle, throughout at least a limited range of displacement. The object in using the perforations is to preserve the strength of the paper tube which could not be done if a relatively long slot were cut therein.

It is a further object of my invention to provide a weft detector depending for its operation upon the entry of one or more plungers into perforations formed in the weft 45 carrier and wherein the arrangement is such that misplacement of the shuttle will not interfere with the operation of the detector and wherein at the same time the bobbin is provided with comparatively small openings 50 which do not materially weaken it.

With these and other objects in view which will appear as the description proceeds my invention resides in the combination and arrangement of parts hereinafter described and set forth in the claims.

55

In the accompanying drawings, wherein two forms of the invention are shown,

Fig. 1 is a top plan view of a shuttle having a weft carrying cop made according to the preferred form of my present invention 60 and showing the same cooperating with my improved detector,

Fig. 2 is a vertical section on line 2—2 of Fig. 1,

Fig. 3 is an enlarged vertical section taken 65 on line 3—3, and

Fig. 4 is a view similar to Fig. 1 but showing a modified arrangement of perforations with respect to the plunger.

Referring to Fig. 1, I have provided the 70 lay L with a binder B to engage the front wall of a shuttle S. The latter is held against the box back 10 by means of the binder and the shuttle may be propelled by the picker 11.

The shuttle may be provided with a metallic spindle 12 having a butt 13 pivoted to the body of the shuttle and having a tongue 14 to enter a slot 15 formed in the paper tube 16. The latter is provided with an internal taper substantially equal to the external taper of 80 the spindle and is forced on the latter to be held thereto by friction, the tongue 14 entering the slot 15 so as to determine the angular relation between the paper tube and the spindle. The front portion of the tube is provided with a plurality of similar perforations 85 which are separated by substantially equal solid parts 21 of the tube, the metallic spindle 12 being accessible through the perforations 20.

The weft detecting element comprises a fixed bracket 22 having a horizontal platform 23 on which are mounted plates 24 and 25 insulated from the platform. The plate 95 24 has upstanding spaced rear and forward bearings 26 and 27, respectively, while the plate 25 is provided in a similar manner with upstanding rear and forward bearings 28 and 29, respectively. The bearing 27 may 100

be connected to a wire 30 while the bearing 29 may likewise be connected to a wire 31.

Slidably mounted in bearings 26 and 27 are equally spaced detector elements in the form of metallic plungers or needles 32 which may be formed of rods or wires each of which is provided with a shoulder 33. Each detector element 32 is provided with a compression spring 34 interposed between its shoulder and the front bearing plate 27.

Similarly the negative side of the circuit is connected to plungers 35 which have shoulders 36 to receive the rearward thrust of springs 37 bearing against the front plate 29. It is to be understood that the construction is such that wire 30 is in electrical contact with all of the plungers 32 while wire 31 is connected electrically to the plungers 35.

By referring to Fig. 1 it will be seen that the distance between the perforations 20 is different from and in this instance greater than the distance between the individual detector elements 32 of the positive group, and this same relation exists also with respect to the other set of negative detector elements 35.

In operation of the preferred form, when sufficient weft is present, all of the plungers or detector elements 32 and 35 will be pressed forwardly against their springs by the yarn on the tube and will be out of contact with the spindle 12, but as exhaustion approaches the perforations 20 will be uncovered so that at least one of the elements 32 and one of the elements 35 will be able to have electrical contact with the spindle 12. In this way the wires 30 and 31 are electrically connected and the external circuit not shown but well understood will be rendered effective to cause stopping the loom or weft replenishment.

As shown in Fig. 1 the shuttle is properly placed so that the left hand detector of each group is located opposite a perforation 20. Should the shuttle rebound, however, so as to be misplaced slightly to the left, then the central detector of each group will be opposite a perforation 20. When the displacement is greater, the right hand detector of each group will be in alignment with a perforation. This result is achieved by making the interval between the perforations different from the interval between the detector elements. In this way I am able to preserve substantially the original strength of the tube by using comparatively small perforations and at the same time provide for a certain limited amount of displacement of the shuttle.

In the modified form of the invention shown in Fig. 4 the interval between the perforations 40 are substantially equal to the interval between adjacent detectors of a group, this arrangement affording more than one opportunity for each side of the circuit

to have contact with the spindle. With this latter arrangement if a single stray strand of filling should happen to be in the path of one detector element even though exhaustion is imminent, yet one or another of the elements can have contact with the spindle and thereby bring about a change in the operation of the loom. In the modified form the detector may occupy the same position it has in the preferred form, but the location of the holes in the cop will be different.

From the foregoing it will be seen that I have provided a simple form of electrical weft detector wherein a metallic spindle is used and where a paper tube or other form of hollow spindle is provided with a plurality of comparatively small perforations which do not materially lessen its strength. In one instance the interval between the perforations measured longitudinally of the shuttle is different from that between the detector rods so as to provide for a certain amount of shuttle misplacement, whereas in the other form of the invention this interval is the same for the detector rods so that each side of the circuit has a plurality of opportunities to establish contact with the spindle.

Furthermore, it will be seen that I have provided in a broader sense a weft detector operating on the principle of a plunger entering a weft carrier wherein the latter is not materially weakened but wherein throughout a limited range of misplacement one or another of a group of plungers may be effective to enter the carrier to effect indication. In this latter regard I do not consider that my invention is necessarily limited to an electrical detector.

Having thus described my invention it will be seen that changes and modifications may be made therein by those skilled in the art without departing from the spirit and scope of the invention and I do not wish to be limited to the details herein disclosed, but what I claim is:

1. In an electrical weft detecting mechanism to cooperate with a shuttle having a metallic spindle, two groups of aligned separately movable electric current conducting detector elements, and a weft carrier of insulating material having a single row of aligned openings extending longitudinally of the carrier, there being one opening for each detector element, the distance between adjacent elements of a group being slightly different from the distance between adjacent corresponding openings in the carrier measured in a direction parallel to the spindle.

2. In an electrical weft detecting mechanism to cooperate with a shuttle having a metallic spindle, two groups of aligned separately movable electric current conducting detector elements, and a weft carrier of insulating material having a single row of aligned openings extending longitudinally

- of the carrier, there being one opening for each detector element, the distance between adjacent elements of a group being slightly different from the distance between adjacent
5 corresponding openings in the carrier measured in a direction parallel to the spindle, the distance between corresponding elements in the groups being equal to the distance between their corresponding openings.
- 10 3. In an electrical weft detecting mechanism to cooperate with a shuttle having a metallic spindle, two groups of aligned separately movable electric current conducting detector elements, the elements of a group
15 being equally spaced, and a weft carrier of insulating material having a single row of aligned openings extending longitudinally of the carrier, there being one opening for each detector element, the openings being
20 equally spaced, the distance between adjacent elements of a group being slightly different from the distance between adjacent corresponding openings in the carrier measured in a direction parallel to the spindle.
- 25 4. In an electrical weft detecting mechanism to cooperate with a shuttle having a metallic spindle, two groups of aligned separately movable electric current conducting detector elements, the groups being insulated
30 from each other and the elements of a group being equally spaced and the groups being spaced apart more than the distance between adjacent elements of a group, and a weft carrier of insulating material on the spindle
35 having a single row of equally spaced holes arranged longitudinally of the spindle, the distance between adjacent holes being slightly greater than the distance between the centers of adjacent detector elements in the same
40 group but substantially less than twice said distance.

In testimony whereof I have hereunto affixed my signature.

ELVIN D. MACARTHUR.
